DESIGN FOR A CLOTHESLINE FASTENER

Ernest H. Anderson, Jamestown, N. Y.

Application October 31, 1944, Serial No. 116,082

Term of patent 14 years

(Cl. D49—1)

To all whom it may concern:

Be it known that I, Ernest H. Anderson, a citizen of the United States, residing at Jamestown, in the county of Chautauqua and State of New York, have invented and produced a new, original, and ornamental Design for a Clothesline Fastener, of which the following is a specification, reference being had to the accompanying drawing, forming part thereof; and in which

Fig. 1 is a perspective view of a clothesline fastener showing my new design;

Fig. 2 is a plan view thereof; and

Fig. 3 is a side elevational view.

I claim:

The ornamental design for a clothesline fastener, substantially as shown.

ERNEST H. ANDERSON.
